NAME John Doe — No. 5 —

JOB NO. 12 —

WITNESSES:

A. M. Hurst.

K. E. Chase

D. M. Tuttle

BY
Howard P. Ganson

ATTORNEY.

UNITED STATES PATENT OFFICE.

DANIEL M. TUTTLE, OF CANASTOTA, NEW YORK, ASSIGNOR TO STELLA S. TUTTLE, OF CANASTOTA, NEW YORK.

ACCOUNTING MEANS.

1,265,008.

Specification of Letters Patent.

Patented May 7, 1918.

Application filed February 18, 1914. Serial No. 819,407.

To all whom it may concern:

Be it known that I, DANIEL M. TUTTLE, of Canastota, in the county of Madison, in the State of New York, have invented new and useful Improvements in Accounting Means, of which the following, taken in connection with the accompanying drawings, is a full, clear, and exact description.

This invention relates to certain improvements in accounting means adapted to be used more particularly for wage workers in keeping an accurate account of the actual time of arrival and departure to and from work or the time of beginning and leaving or finishing of specific jobs and also for computing the lapsed time and cost of any wage-work or job.

The main object is to provide a workman's time card with a plurality of columns of numerals spaced uniform distances apart and progressively increasing in value from one and the same end and successively through the several columns so that the numerals representing the times of arrival and departure or the beginning and ending of work on a wage scale or job may be punched out or cut away leaving the card with apertures to enable the workman or time-keeper to distinguish at a glance the "full time" from the "loss time" periods and to easily compute the lapsed time for any periods within the range of numerals.

In the drawings—

Figures 1 and 2 are face views respectively of a workman's wage card and a workman's job card embodying certain features of my invention.

Figs. 3 and 4 are similar face views of what may be termed respectively a wage card and a lapsed time card to be used in connection with the cards shown in Figs. 1 and 2 for determining the wages due at a certain price per hour and also the total lapsed time between beginning and ending work.

Fig. 5 is a face view of a portion of the workman's time card as applied to the lapsed time card, showing the manner of ascertaining the amount of lapsed time between the beginnings and endings of work as indicated by the perforations in the workman's time card.

Fig. 6 is a face view of a portion of the

workman's time card as applied to the wage card to show the amount of wage due the workman for the time lapsed between the beginning and ending of work as indicated by the perforations in the workman's time card.

Fig. 7 is a face view of a workman's job card as applied to a wage card to indicate the total cost of the time lapsed between the beginning and ending of a particular job as shown by the perforations in the job card, the wage card being the same as that shown in Fig. 3.

Fig. 8 is a sectional view taken on line 8—8 of Fig. 7.

In order that my invention may be clearly understood, I have shown a weekly time card —1—, a job card —2—, a lapsed time card —3— and a wage card —4—, each of which is provided with a plurality of columns of numerals progressively increasing in value from one and the same end and successively through the several columns.

The time card —1— and job card —2— may be termed the "primary" cards because they are the ones used by the workmen in punching out the factors indicating the times of beginning and ending of work during the day or upon a particular job, while the wage card and lapsed time card may be termed the "secondary" cards, the lapsed time card bearing the numerical results of the computations of working time between the time of beginning and ending of work, as indicated by the punched factors on the "primary" cards, the wage card also bearing the results or products of the lapsed time at a given rate per hour as printed thereon.

The numerals on the workman's weekly time card —1— are preferably arranged in sets of four columns each, one set for each working day, the several sets being designated by the abbreviated captions "Mon.", "Tues.", "Wed.", "Thurs.", "Fri.", and "Sat." arranged in sequence from left to right, the sets for the first three days of the week being printed on one end of the card while those for the remaining three days of the week are printed in reverse order on the opposite end, thus permitting the use of a relatively narrow card which is more conveniently handled and operated

upon by a punching machine (not shown) but adapted to be used for punching out or cutting away the numerals representing the times of arrival and departure to and from work.

The columns of numerals of each set are parallel with the same number of numerals in each column spaced equidistant apart, the numerals of the different columns being arranged in horizontal lines so that the numerical difference between opposite numerals of adjacent columns is the same and corresponds to the highest number in the first column.

The numerals of the several columns of each set progressively increase in value, in this instance from bottom to top, in hundredths of a day of ten (10) hours and for convenience are printed upon the cards as decimals, the first column of each set being numbered from 0 to 25, the second from 25 to 50, the third from 50 to 75, and the fourth from 75 to 100, and may, therefore, be read as tenths of an hour or hundredths of a full working day of ten hours.

It is evident, however, that other numerals representing the same or different consecutive periods of time may be similarly arranged in columns or in one continuous column and that the numerals of each column may be the same without departing from the spirit of my invention, which consists in printing upon a card one or more columns of numerals progressively increasing in value so as to represent the consecutive periods of time so that the employee designated on the card may insert such card into a suitable machine capable of obliterating by punching or otherwise the particular numerals representing his times of arrival and departure to and from his work or in the use of the job card —2— which is similarly printed, he may similarly obliterate by punching or otherwise the numerals indicating the time of beginning and ending of work upon any particular job designated in this instance by "Job No. 12" on the job card.

The columns of numerals of each set reading from left to right respectively "morning in," "noon out," "noon in," and "night out," and the preferable method, as shown, of registering the times of arrival and departure of the workman is by cutting away or punching out the particular numerals representing such periods of time, thus permitting apertures —5— which show at a glance whether or not the workman has put in full time and, if not, enables the timekeeper to easily compute the difference between the time of arrival and departure either for the half day or for the full day.

For example, the apertures, on the card illustrated, show that this particular workman began work one hour late or eight

(8:00) o'clock, providing the standard time of beginning is seven (7:00) o'clock, and that he left off work 4.9 hours from the standard time of beginning or one-tenth of an hour before twelve (12:00) o'clock, that is six (6) minutes to twelve (12); beginning again before one (1:00) o'clock and continuing until 9.7 hours from the standard time of beginning in the morning, that is —.3 of an hour or eighteen (18) minutes before six (6:00) o'clock, the standard time of closing, so that the actual working hours in the morning is the difference between .1 and .49, or .39, that is 3.9 hours in the morning or for the full day, the difference between .1 and 9.07, which would be 8.7 hours for the full day.

In like manner, the lapsed time of work between the consecutive apertures in the columns of any other set may be determined and computed.

In a similar manner, the amount of time put upon any job by any workman may also be computed, as illustrated for example, in the job card, Fig. 2, which shows that this particular workman began work upon Job No. 12, at .05 or thirty (30) minutes from the standard time of beginning, say seven (7) o'clock and worked continuously on that job until .66 of the day of ten (10) hours or 6.6 hours from the standard time of beginning so that the actual time of work is the difference between .05 and .66 or 6.1 hours.

These apertures not only show at a glance the exact times of arrival and departure of the workman by their strong contrast with the figures, but may also be utilized in connection with the lapsed time card, Fig. 3, in the manner shown in Fig. 5 to indicate at a glance the total time of work either for the half day or for the full day and for this purpose the lapsed time card is provided with a group —6— of, in this instance four, columns of numerals progressively increasing by hundredths from 0 to 100 from bottom to top through the several columns successively from left to right, as shown more clearly in Fig. 4, the columns and numerals being arranged in the same spaced relation as shown on the workman's time card so that by placing the workman's time card over and upon the lapsed time card with the first cut aperture of said workman's time card registering with the zero point on the lapsed time card, the numeral or numerals on the lapsed time card appearing through the remaining aperture or apertures of the workman's time card will indicate the total working time of that particular employee for that particular half day or day as the case may be.

In order that the first cut aperture in the workman's time card may be quickly and accurately registered with the zero point on the lapsed time card, I have provided the latter with a tapered projection —7— in

- place of the zero mark and of substantially the same size as one of the perforations in the workman's time card so that all that is necessary to do is to place the workman's 5 time card over and upon the lapsed time card in such manner as to cause the projection —7— to protrude through the first cut aperture of any particular day or half day whereupon the total time of working 10 for such half day or day printed upon the lapsed time card will appear through the remaining aperture or apertures.
- This is better illustrated in Fig. 5 in which I have shown the workman's time card having the first cut aperture for the morning at 15 "10" registered with and fitted upon the projection —7— with the numerals "39" and "87" of the lapsed time card appearing through the apertures in the second and 20 fourth columns under the caption "Mon." thus indicating the actual working time of 3.9 hours in the forenoon and 8.7 hours for the full day, or taking the same set of columns of numerals for "Mon." if it is desired 25 to ascertain the working time of this employee for the afternoon when he began work before one (1:0) o'clock, as indicated by the aperture at the bottom of the third column, one space below the lowest numeral "50" 30 therein, then all that is necessary to do is to re-arrange the workman's time card one upon the lapsed time card so that this aperture will register with and fit upon the projection —7—, thus bringing the aperture in 35 the fourth column of the Monday time into registration with the numeral "48" on the lapsed time card showing that the total time of work for the afternoon was 4.8 hours.
- In like manner, the total working time of 40 that employee for any day may be ascertained at a glance and with greater accuracy than would be possible with mental computation and in a similar manner the total time engaged by any particular workman on any 45 job may be ascertained by a similar application of the job card to the lapsed time card.
- It may happen at times that in a workman's time card or a job card, the time of beginning of work will be late in the forenoon 50 and that the time of finishing will be late in the day, thereby bringing the first formed aperture considerably higher up in the first column than that in the last column of the series for that particular day or job in which case if 55 the first formed aperture was registered with the projection —7—, the last formed aperture would be way below the lapsed time columns, and in order to render the lapsed time card useful under these conditions, I have 60 provided with an extra group —8— of, in this instance, three, columns of numerals arranged at the left of the first group —6—, but in reverse order, that is progressively increasing in value by hundredths 65 from the top through the several columns of such extra group from 0 to 75 so that they read in sequence from the top downward and from right to left, but in horizontal lines coincident with those of the first group and in the same spaced relation as to columns 70 and numerals—that is the columns of both groups are spaced equal distance apart so that in case the aperture first punched in the workman's time card or job card cut away the numeral "23" and the aperture last 75 punched for the same day or on the same job cut away the numeral "78" in the fourth column, then by placing the aperture corresponding to the numeral "78" on the stud or projection —7— would bring the first cut 80 aperture registering with the numeral "23" on the workman's time card or job card into registration with the numeral "55" in the third column of the second group 8 on the lapsed time card, thereby showing the total 85 time of work to be 5.5 hours as the difference between "23" and "79".
- I also utilize these apertured time and jobbing cards in determining the total wages due the particular workman at a certain 90 wage per hour and for this purpose have shown the wage card —4— as having printed thereon a group —9— of four (4) columns of numerals progressively increasing in value differences of .02 from bottom to top 95 and from 0 to 200, representing by decimals the total wages due a workman at, for example, twenty cents (\$.20) per hour, said card being provided with a projection —7— similar to the projection —7— and secured 100 to the card at the zero point for entering the first cut aperture in the workman's time or job card whereby the total wage due at twenty cents (\$.20) per hour printed on the wage card will appear through the remaining aperture or apertures.
- For example, in Fig. 6, I have shown a portion of a previously apertured workman's time card —1— as applied to a wage card by registering its first cut aperture corresponding to the numeral "10" with the projection —7— by which application the numeral "78" on the wage card will appear through the aperture in the second column of the time card showing that the amount 110 of wages due that particular employee for the half day is seventy-eight cents (\$.78), the lapsed time being 3.9 hours, while the numeral "174" on the wage card will appear through the aperture of the fourth column 115 of the time card, thus indicating that the total wage for the day amounts to one dollar and seventy-four cents (\$1.74) or the lapsed time of 8.7 hours at twenty cents (\$.20) per hour. 120
- A similar application of a job card to the wage card as shown in Fig. 7 will produce similar results.
- In case the first cut aperture on the time or job card is considerably higher than the 130

second or last cut aperture, as previously explained, in applying those cards to the lapsed time card, the wage card is provided with an additional group —10— of columns 5 of numerals at the left of the first group and arranged in reverse order similar to that described for the lapsed time card so that by applying the last cut aperture of the time or job card to the projection —7'—, the total 10 wages due for the lapsed time will appear in the first cut aperture when the time card is applied to the wage card in the manner previously described.

These cards printed and punched in the 15 manner described may be coated with a water-proof coating, such as shellac, and handled out of doors in wet or snowy weather without liability of obliterating the records and at the same time allowing the card to 20 be punched at any time to indicate the time of arrival and departure of a workman, all of which renders this system useful for contractors on public works in addition to all of the various uses to which workman's time 25 records or job cards are adapted.

What I claim is:

An accounting means including a primary card bearing consecutive time values columnized in definitely spaced relation and adapted to have certain ones of the time values 30 corresponding to the times of beginning and ending work cut away, and a coöperating secondary card bearing consecutive numerical values columnized in the same spaced relation as those of the primary card and having a projection at the point where the numeral of lowest value is arranged thereon for entering the aperture indicating the time 35 of beginning work on the primary card, whereby the result sought on the secondary 40 card will appear through the aperture indicating the time of ending such work when the columns of numerals of both cards are in parallel relation.

In witness whereof I have hereunto set 45 my hand this 11th day of February, 1914.

DANIEL M. TUTTLE.
